FLASK SWIRLER

Douglas Edward Kerr-Lawson, Swastika, Ontario, Canada, assignor to Swastika Laboratories Limited, Swastika, Ontario, Canada, a corporation

Application November 28, 1955, Serial No. 549,444

6 Claims. (Cl. 74—42)

This invention is concerned with an apparatus for converting a rotary motion into a compound oscillatory motion, and is particularly, but not exclusively, concerned with an apparatus for imparting a compound oscillatory movement to a body such as a flask or stirring paddle of the kind used in chemistry laboratories.

An object of the invention is to provide a simple apparatus in which a rotary motion can be converted into a compound oscillatory motion.

Another object of the invention is to provide an apparatus in which a chemist's flask or stirring paddle can be mounted, the apparatus converting a simple rotary motion of a source of power into a compound oscillatory motion of a point located on the said flask or stirrer.

A further object of the invention is to provide an apparatus in which a flask can be supported, the apparatus imparting to the flask a compound oscillatory motion resulting in the longitudinal axis of the flask describing a path which is that of the surface of an imaginary cone, whereby fluid contained within the flask has a swirling motion imparted to it for effecting turbulence in the fluid.

A still further object of the invention is to provide an apparatus in which a flask can be supported, the apparatus imparting a compound oscillatory motion to the flask in such a manner that a point located on the axis of the flask and within the throat thereof remains relatively stationary.

A still further object of the invention is to provide an apparatus for imparting a compound oscillatory motion to a flask, in which those portions of the flask adjacent the throat thereof have relatively little movement imparted to them as the flask is oscillated, whereby fluid can be introduced into the flask while it is being oscillated with little danger of the fluid being thrown from the neck of the flask, by centrifugal action, with possible hazard to the safety of the user of the apparatus.

According to the invention, the apparatus for converting the rotary motion into a compound oscillatory motion, comprises in combination, a first shaft associated with the source of rotary motion for said shaft to be rotated about its longitudinal axis, a crank arm extending radially of the end of said shaft, a lever pivotally connected to said crank arm at a point remote from the axis of said shaft, a second shaft fast with the other end of said lever and extending in a direction which is substantially the same as the direction of the axis of said first shaft, said second shaft being adapted to support a member for said member to extend laterally of said second shaft, a second arm pivoted about an axis intersecting the longitudinal axis of said member and normal to the longitudinal axis of said second shaft, the pivotal axis of said second arm lying in a plane transverse of a line extending between the axis of said second shaft and normal to the axis of said first shaft, and a journal bearing carried by said second arm and in which said second shaft is journaled, the combined oscillation imparted to said second shaft and said arm by said lever when said first shaft is rotated causing a point on the longitudinal axis

of said member to trace an elliptical path so that the said axis defines the surface of an imaginary cone.

Other objects and advantages of the invention will become apparent from a study of the specification when taken in conjunction with the accompanying drawing which is a diagrammatic perspective view indicating the respective positions of the essential elements of the combination according to the invention.

In the drawing, the apparatus includes a shaft 10 to which a flask 11 is secured as by means of a quick release clamp 12. Although a flask is shown in the drawing, it will be obvious that a stirring rod, paddle, or some other member may be attached to the shaft. It is, however, essential that the longitudinal axis 11a of the flask or other member should extend laterally of the longitudinal axis 10a of the shaft, although it need not necessarily be normal thereto.

The shaft 10 is journalled in a bearing 13 carried by an arm 14 which is pivoted at 15 on an axis 15a which is normal to the axis 10a of the shaft and intersects the axis 11a of the flask. Although an arm which is substantially L-shaped in plan is shown in the drawing, various modifications in the shape of the arm can be made without departing from the spirit of the invention, for example, the arm could be arcuate or of cantilever construction or be a simple plate, the only essential being that the axis 15a of the pivot bearing 15 and the axis 13a of the journal bearing 13 should lie in a common plane. As the axes 15a and 13a lie in a common plane, it will be apparent that the axis 10a will also lie in that plane, as will the intersection of the axes 10a, 11a.

Rigidly secured to the shaft 10 is a lever 16, the lever having at its lower end a pin 17 by which it can be connected to a crank arm 18 carried by a shaft 19. The shaft 19 is adapted to be rotated through pulleys 20 and 21 from a source of power (not shown) connected to a shaft 22, the drive from the pulley 21 to pulley 20 being through the intermediary of a V belt 23.

It will be appreciated that the drawing is purely diagrammatic, and that various structural elements, for example bearings for the shaft 19, 22 and the male member of the journal bearing 15 are omitted.

The operation of the apparatus is as follows:

The flask 11 or other member is set up in the clamp 12 and the source of power is energized to rotate the shaft 22, for example in an anti-clockwise direction as indicated by the arrows 22a. The shaft 22 rotates the pulley 21 which rotates the pulley 20 through the intermediary of the belt 23, the difference in the size of the pulleys providing a speed reduction between the shaft 22 and the shaft 19. The shaft 19 is rotated by the pulley 20 in an anti-clockwise direction, as indicated by the arrows 19a, and this causes the crank arm 18 to rotate about the axis of the shaft and the pin 17 to follow a circular locus. The lever 16 thus has imparted to it movement in two directions which occur in combination, i. e., a vertical component indicated by the arrows 16a, due to the pin 17 moving from the top of a vertical diameter of the locus to the bottom, and vice versa, and an angular component, indicated by the arrows 16b, due to the pivot 17 traversing from one side of the horizontal diameter of the locus to the other.

Examining the effect of the respective movements separately, the movement of the lever 16 in the direction of the arrows 16a causes the arm 14 to rise and fall about its pivot 15 as is indicated by the arrows 14a. As the shaft 10 is journalled in the bearing 13 which is fast with the arm 14, it also moves in the direction of the arrows 14a and the movement is transmitted to the flask causing it to move in the direction of the arrows 11b. It will be noted that the point X which lies at the intersection of the axes 10a, 11a, 15a is not displaced.

Considering now the effects of the movement of the lever 16 in the direction of the arrows 16b, as the lever is rigidly connected to the shaft 10, movement in the direction of the arrows 16b will cause the shaft to be rotated about its longitudinal axis 10a. This rotation imparts to the flask a movement in the direction of the arrows 11c, and it will be again observed that the point X at the intersection of the axes 10a, 11a, 15a is unaffected by the movement.

It will thus be seen that rotation of the crank arm 18 imparts to the flask movements in the direction of the arrows 11b and 11c, which movements occur in combination, the displacement in the direction of the arrows 11b being at a minimum when the displacement in the direction of the arrows 11c is at a maximum. The result of these combined movements is that the flask traces a circular or elliptical path, as is indicated by the arrows 11d, the distance of the point X from lever 16, the length of the lever 16, and the radius of the locus of the pin 17 determining whether the path followed by the flask be circular or elliptical. Expressed another way, the axis 11a of the flask below the point X will follow a path generating the surface of an imaginary cone when the shaft 19 is rotated.

To cater for misalignment of the ends of the lever 16 due to the rise and fall of the arm 14, the lever is preferably formed from a strip of spring steel, the major width of the lever lying in a plane transverse to the axis 10a of the shaft 10.

As the point X is not displaced when the apparatus is in use, and the point X lies within the throat of the flask, it will be appreciated that very little movement is imparted to the throat of the flask as compared with the bulb thereof. This has the desirable effect that fluids can be introduced into the flask while the apparatus is in motion with little danger of any fluid which may contact the inner wall of the throat being thrown outwardly by centrifugal action. Also, it is comparatively easy to introduce the fluid into the flask while it is in motion.

A further advantage accruing from the invention when used for swirling a flask, resides in the fact that the velocity of movement of the flask is not constant. This is due to the fact that the maximum velocity of the arm 14 occurs when the arm is rising and the lever 16 is at a tangent to the locus of the pivot 17.

On the other hand, the swinging of the lever 16 in the direction of the arrow 16b is constant for each traverse of the pin 17 from one side to the other of a horizontal diameter of the locus. This inconstancy in velocity has the beneficial effect of causing increased turbulence within fluids contained in the flask, and results in highly efficient mixing of the fluids.

The apparatus, instead of being used for swirling a flask, may alternatively be used for moving a stirring rod or paddle, or used for such purposes as providing animation in display equipments, etc.

What I claim as my invention is:

1. Apparatus for converting a rotary motion into a compound oscillatory motion, comprising in combination, a first shaft associated with the source of rotary motion for said shaft to be rotated about its longitudinal axis, a crank arm extending radially of the end of said shaft, a lever pivotally connected to said crank arm at a point remote from the axis of said shaft, a second shaft fast with the other end of said lever and extending in a direction which is substantially the same as the direction of the axis of said first shaft, said second shaft being adapted to support a member for said member to extend laterally of said second shaft, a second arm pivoted about an axis intersecting the longitudinal axis of said member and normal to the longitudinal axis of said second shaft, the pivotal axis of said second arm lying in a plane transverse of a line extending between the axis of said second shaft and normal to the axis of said first shaft, and a journal bearing carried by said second arm and in which

said second shaft is journalled, the combined oscillatory motion imparted to said second shaft and said arm by said lever when said first shaft is rotated causing a point on the longitudinal axis of said member to trace an elliptical path so that said axis defines the surface of an imaginary cone.

2. Apparatus for imparting a combined oscillatory motion to a body, including a shaft adapted to support said body for the longitudinal axis of said body to extend laterally of the longitudinal axis of said shaft, a pivot bearing having its axis normal to said shaft and intersecting the axis of said body, an arm pivotally supported from said bearing, a journal bearing carried by said arm and in which said shaft is journalled, and means for oscillating the said arm about the axis of said pivot bearing and oscillating said shaft about the longitudinal axis thereof to cause said axis of said body to oscillate about the point of intersection of the axis of said longitudinal shaft, body and pivot bearing, the combined oscillatory motion imparted to said arm and said shaft causing a point on the longitudinal axis of said body to trace an elliptical path so that said axis defines the surface of an imaginary cone.

3. Apparatus for imparting a combined oscillatory motion to a body, including a shaft adapted to support said body for the longitudinal axis of said body to extend laterally of the longitudinal axis of said shaft, a pivot bearing having its axis normal to said shaft and intersecting the axis of said body, an arm pivotally supported from said bearing, a journal bearing carried by said arm and in which said shaft is journalled, a lever rigidly secured to said shaft and extending laterally of said shaft in a direction substantially perpendicular to the plane containing the axis of said pivot and journal bearings, and means for causing a point on said lever remote from said shaft to describe a circular locus in a plane transverse to the axis of said shaft, the combined oscillatory motion imparted to said arm and said shaft by said lever when said point describes said locus causing a point on the longitudinal axis of said body to trace an elliptical path so that said axis defines the surface of an imaginary cone.

4. Apparatus for imparting a combined oscillatory motion to a body, including a shaft adapted to support said body for the longitudinal axis of said body to extend laterally of the longitudinal axis of said shaft, a pivot bearing having its axis normal to said shaft and intersecting the axis of said body, an arm pivotally supported from said bearing, a journal bearing carried by said arm and in which said shaft is journalled, a lever rigidly secured to said shaft adjacent said journal bearing and extending laterally of said shaft in a direction substantially perpendicular to the plane containing the axis of said pivot and journal bearings, and means for causing a point on said lever remote from said shaft to describe a circular locus in a plane transverse to the axis of said shaft, the combined oscillatory motion imparted to said arm and said shaft by said lever when said point describes said locus causing a point on the longitudinal axis of said body to trace an elliptical path so that said axis defines the surface of an imaginary cone.

5. Apparatus for imparting a compound oscillatory motion to a body, including a shaft adapted to support said body for the longitudinal axis of said body to extend laterally of the longitudinal axis of said shaft, a pivot bearing having its axis normal to said shaft and intersecting the axis of said body, an arm pivotally supported from said bearing, a journal bearing carried by said arm and in which said shaft is journalled, a lever rigidly secured to said shaft adjacent said journal bearing and extending laterally of said shaft in a direction substantially perpendicular to the plane containing the axis of said pivot and journal bearings, a crank arm mounted for rotary movement in a plane transverse to the axis of said shaft, means for rotating said crank arm and means pivotally connecting the end of the lever remote from said shaft to

said crank arm on a radius of the axis of rotation thereof, the combined oscillatory motion imparted to said arm and said shaft by said lever when said crank arm is rotated causing a point on the longitudinal axis of said body to trace an elliptical path so that said axis defines the 5 surface of an imaginary cone.

6. Apparatus according to claim 3, in which said lever is resilient in a direction axially of said shaft.
